UNITED STATES PATENT OFFICE.

EDGAR L. SALOM, OF MONTCLAIR, NEW JERSEY, ASSIGNOR TO THE NEW YORK TELEPHONE COMPANY, OF NEW YORK, N. Y.

DESIGN FOR A TABLE.

SPECIFICATION forming part of Design No. 34,510, dated May 14, 1901.

Application filed April 5, 1901. Serial No. 54,562. Term of patent 7 years.

To all whom it may concern:

Be it known that I, EDGAR L. SALOM, a citizen of the United States, residing in the town of Montclair, Essex county, and State of New Jersey, have invented and produced a new, useful, and original Design for a Table, of which the following is a specification, reference being had to the accompanying drawings, forming part thereof.

Figure 1 is a perspective view of such table, showing its shape and configuration. Fig. 2 is an end view of same.

As shown in Fig. 1 of the drawings, the leading or material features of my design consist in a table having a top A, supported by two side pieces B B, which are braced at their lower ends by the included cross-piece or foot-rest G, the side piece B terminating in and resting upon the turned feet C C. Below the table-top and supported from it is the face-piece H. The supporting sides, as shown in

Fig. 2, are in the form of pilasters having a fluted shaft E, resting on an ornamental pedestal F and supporting the entablature D, whose outlines are in the form of an ornamental scroll. This entablature bears a heraldic design consisting of a shield from which spring recoco volutes supporting drapery festooned in a dependent curve. 25

Having described my invention, what I claim as new, and desire to secure by Letters Patent, is—

The design for a table as herein shown and described.

In witness whereof I have signed my name 35 to this specification in the presence of two subscribing witnesses.

EDGAR L. SALOM.
